UNITED STATES PATENT OFFICE.

JULIUS W. BASSETT, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 14,836, dated March 4, 1884.

Application filed January 22, 1884. Term of patent 3½ years.

To all whom it may concern:

Be it known that I, JULIUS W. BASSETT, of Brooklyn, Kings county, New York, have invented a new and original Design for Carpets, 5 of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face 15 view of a carpet showing my new design. The feature of the design is the open leaf-

work shown in the photograph. The leaf, in various positions, is arranged so as to evenly fill up the ground, and inconspicuous stems connect the leaves together. A few circular figures appear in the photograph, and one or two conventionalized flower figures. They relieve the uniformity in the general effect of the design.

I claim—

The design for a carpet, substantially as 25 shown and described.

JULIUS W. BASSETT.
